MEANS FOR OSCILLATING A BABY CARRIAGE

Frank P. Grunkemeyer, Morris, Ind.

Application November 21, 1932
Serial No. 643,789

1 Claim. (Cl. 180—1)

This invention relates to means for oscillating a baby carriage. In vehicles for babies, it is customary to wheel the same back and forth for the purpose of pacifying or quietening the occupant, and it is the particular object of this invention to accomplish this movement of the vehicle automatically.

Another important object of the invention resides in the provision of means of this nature which is simple in its construction, inexpensive to manufacture, thoroughly efficient and reliable in use and operation and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

20 In the drawings:

Figure 1 is a side elevation of the mechanism embodying the features of my invention.

Figure 2 is a top plan view thereof.

Figure 3 is a vertical section taken substantially on the line 3—3 of Figure 1.

Figure 4 is a vertical transverse section taken substantially on the line 4—4 of Figure 2.

Figure 5 is a detail section taken substantially on the line 5—5 of Figure 2.

30 Referring to the drawings in detail it will be seen that numeral 5 denotes a casing. A pair of rails are constructed of angle iron and each rail comprises two sections 6 and 7. A plurality of cross bars 8 are disposed between the sections 6—6 and 7—7 and are located at the ends thereof. The pair of cross bars 8 adjacent each other are hingedly connected together as at 9 so that the sections 7 may be folded under the sections 6 and the casing 5 when the mechanism is not in use. Under the casing and under the rails are suitable feet indicated by the numerals 10.

45 Each cross member 8 comprises an elongated section *a* and a relatively short section *b* under one end thereof. The section *a* has a plurality of openings 12 so that a screw may be extended through one of them as indicated at 14 to engage in an opening in the section *b*. The section *b*, of course, is attached to one rail while the section *a* is attached to the other rail. By proper adjustment, therefore, the rails may be disposed different distances apart depending upon the width of the baby carriage so that the wheels of the carriage may ride properly on these rails.

55 Inside the casing 5 is an electrically driven mechanism including a connecting rod 15 which is to be oscillated by the mechanism and a plate 16 is fixed to the bottom of the body of the carriage and has a pair of spaced apertured ears 17 to receive the outer end of the connecting rod 15 which

is pivotally engaged between the ears by a removable pin 18.

The rod 15 is eccentrically engaged with a grooved wheel 19 on a shaft 20 mounted in a frame 21 inside the casing 5. Numeral 22 denotes a motor operatively connected with a shaft 23 by a belt 24 over a pulley 25. The shaft 23 has a pulley and belt connection 26 with a shaft 27 in the frame 21 and this shaft 27 has a belt and pulley connection 28 with said wheel 19. Suitable belt tightening means 30 is associated with the belting to permit the belting to slip should the carriage come in contact with some obstacle or the like.

It is thought that the construction, operation, utility and advantages of this invention will now be quite apparent to those skilled in this art without a more detailed description thereof.

The present embodiment of the invention has been described in considerable detail merely for 80 the purposes of exemplification since in actual practice it attains the features of advantage enumerated as desirable in the statement of the invention and the above description.

It will be apparent that changes in the details 85 of construction, and in the combination and arrangement of parts may be resorted to without departing from the spirit or scope of the invention as hereinafter claimed or sacrificing any of its advantages.

Having thus described my invention, what I claim as new is:

A baby carriage oscillating device comprising a casing, a short track section and a long track section, each section including a pair of side rails 95 for receiving the wheels of the carriage and a pair of cross pieces connecting the ends of the rails together, means for adjustably connecting one side rail to the cross pieces for permitting the width of the sections to be adjusted, hinges fastened to the under sides of the adjacent cross pieces of the two sections to permit the long section to be folded under the short section, the other cross piece of the short section being connected to one side of the casing adjacent the bottom thereof, a bracket fastened to a part of the carriage, a pitman passing through that side of the casing to which the short section is connected, with its outer end pivotally connected to the bracket, and means within the casing for reciprocating the pitman.

FRANK P. GRUNKEMEYER.
